UNITED STATES PATENT OFFICE.

ALFRED JOSEPH SEALE, OF GRANBY, QUEBEC, CANADA.

LIQUID-DISPENSING APPARATUS.

Application filed February 28, 1924. Serial No. 695,848.

To all whom it may concern:

Be it known that I, ALFRED J. SEALE, a subject of the King of Great Britain, residing at Granby, Province of Quebec, Canada, 5 have invented certain new and useful Improvements in Liquid-Dispensing Apparatus; and I do hereby declare that the following is a full, clear, and exact description of the invention, such as will enable 10 others skilled in the art to which it appertains to make and use the same.

The present invention pertains to a novel liquid dispensing apparatus, preferably of the coin or key controlled type for serving 15 gasoline or oil. It will, however, be understood that the apparatus may be used for dispensing liquid of any desired character.

The principal object of the invention is the provision of a device of this character 20 including a discharge pump adapted for operation by a key controlled device. To this end, the mechanism includes a disc normally locked with respect to the casing and disengaged therefrom only by the insertion of a key. The disc can be turned 25 after the proper key is inserted, whereupon a motor is started for setting the pump in action. A device is provided for normally returning the disc to its initial position, but 30 the casing carries a pawl for holding the device against return movement. The pump operates as long as the disc is thus held 35 against return movement, and ceases only when the holding device is released by a trip movable from the pump mechanism.

Two or more such discs are preferably 40 associated with the device for the delivery of different quantities of liquid. The embodiment described in the present instance 45 comprises two discs at opposite sides of the trip carrying member. The trips are disposed at unequal distances from the top of the member carrying them, so that the operative period of the pump varies in accordance with the disc in which the key is inserted.

The invention further includes an automatic device for extracting the key upon rotation of the disc and delivering it into 50 a locked receptacle.

The invention is fully disclosed in the following description and in the accompanying drawings in which:

Figure 1 is a front elevation of the 55 device;

Figure 2 is a section on the line 2—2 of Figure 1, the door being closed;

Figures 2^a and 2^b are enlarged details of Figure 2, showing the door lock in closed and open positions respectively; 60

Figure 3 is a detail of one of the pawl springs;

Figure 4 is a section on the line 4—4 of Figure 1;

Figure 5 is a section on the line 5—5 of 65 Figure 1;

Figure 6 is a section on the line 6—6 of Figure 4;

Figure 7 is a detail of Figure 6;

Figure 8 is a detail corresponding to Figure 7, showing the parts in a different position; 70

Figure 9 is a detail showing the cam and key extractor in engagement;

Figure 10 is a section on the line 10—10 of 75 Figure 2;

Figure 11 is an enlarged detail of Figure 10;

Figure 12 is a section on the line 12—12 of Figure 10; 80

Figure 13 is a section on the line 13—13 of Figure 11;

Figure 14 is a section on the line 14—14 of Figure 4;

Figure 15 is a section on the line 15—15 85 of Figure 1;

Figure 16 is a section similar to Figure 15, showing the door closed;

Figure 17 is a section of the valve controlled pump inlet; 90

Figure 18 is a detail section of one of the piston valves;

Figure 19 is a wiring diagram; and,

Figure 20 is a section on the line 20—20 of Figure 2^a. 95

Reference will now be had to these views by means of like characters which are employed to designate corresponding parts throughout.

As shown in Figures 1 and 2, the device 100 comprises a box like base 1 in which is supported a pump cylinder 2 connected by means of a pipe 3 to an underground storage tank not shown. A piston rod 4 passes through the top of the cylinder and carries 105 at its lower end a piston 5 fitting tightly into the cylinder. The base of the cylinder is formed with a valve seat 6, upon which rests a ball or gravity valve 7. This member is prevented from being drawn upwardly 110

into the cylinder by means of a cage 8. On the upward stroke of the piston the valve is opened by suction, whereby a flow from the storage tank into the cylinder is induced.

5 The piston is formed with passages 9 into which are inserted valve seats 10 containing gravity or ball valves 11 similar to the members 7. These also are prevented from being drawn into the cylinder proper 10 by means of cages 12. On the upward stroke of the piston these valves are closed, whereby the liquid is forced through the outlet 13 (Figure 10). On the downward stroke of the piston the valve 7 is closed 15 and the valves 11 opened whereby the liquid is free to flow from the bottom to the top of the piston and thus permit free downward movement of the latter. A housing 14 is mounted upon the base 1 and contains 20 the operating mechanism described in detail below. An outlet pipe 15 extends from the outlet 13 upwardly into this housing and through one of the walls thereof, as shown in Figures 1 and 2. The outer end 25 of the outer pipe is fitted with an elbow 16 to which is attached a flexible hose 17 adapted for insertion into the gasoline tank of an automobile or into any other receptacle into which the liquid is to be delivered.

30 The outlet end of the hose may conveniently be supported when not in use upon a hook 18 secured to the base 1. The parts within the base may be reached through the door 19 normally closed at the lock 20.

35 To the upper end of the piston rod is secured a rack 21 extending into the housing 14 and disposed adjacent the forward wall 22 thereof, as shown in Figure 2. The forward wall is formed near its top with 40 a slot 23 adjacent which a series of volume indications 24 are marked. The upper end of the rack is formed with an indicator 25 visible through the slot and cooperating with the indications 24. The rack is guided 45 in part by a roller 26 engaging the back thereof and secured to the top of the base 1.

On the top of the base 1 and within the housing 14 is supported a motor 27, the shaft 28 of which carries a pinion 29. A 50 counter shaft 30 is suitably journaled within the housing and carries at one end a gear 31 meshing with the pinion 29. The remaining end carries a pinion 32 which meshes with the rack 21, as shown in Figure 5 and 10.

An intermediate wall 33 is disposed a short distance behind the front wall 22 and cooperates with the front wall to enclose the rack 21. A pair of parallel shafts 34 60 and 35 are journaled in the rear wall and intermediate wall as shown in Figure 4. The forward ends of the shafts protrude into the space between the walls 22 and 23 and are there provided with discs 36 and 65 37. Inasmuch as these discs and parts as-

sociated therewith are identical in structure, it will be necessary to describe only one of them in detail. Each disc carries a lock 38 from which protrudes a spring pressed bolt 39. The disc is surrounded by a ring 40 secured in the space between the walls 22 and 33, thus enclosing the disc completely. At the top of the ring is formed a keeper 41 for enclosing the bolt and holding the disc in a locked position. When a key of proper shape is inserted in the lock, the bolt can be partially withdrawn whereby the disc is free to rotate with reference to the ring. Rotation may be effected by means of a crank 42 secured to the extreme forward end of the corresponding shaft.

A receptacle 43 is secured to the lower portion of the front wall 22 and extends upwardly as far as the shafts 34 and 35, thus concealing the lower half of each disc. The interior of the receptacle 43 is divided by means of partitions 44 and 45 into a pair of key receiving compartments 46 and 47 at the ends and beneath the discs. The top of the receptacle is formed at its end with slots 46' and 47' (Figure 4) adapted to allow the passage of the keys inserted in the discs. The lower portion of each ring 40 is formed with a stop 48 for engaging the corresponding bolt 39 and limiting the movement of the disc. This stop is formed by enlarging the adjacent portion of the ring as indicated by the numeral 49 in Figure 11.

To the top of each compartment is pivoted a depending flap 50 carrying a finger 51. As the key 52 travels into the compartment as a result of rotation of the crank 42, the shoulder thereof is engaged by the flap in the manner shown in Figure 12. Each disc carries a cam 53 on a radial line passing through the lock, and this cam engages the finger and pushes the flap outwardly after the disc has been stopped at 48. The key is thus extracted from the lock and drops into one of the compartments.

The innermost point of each ring is formed with an aperture 54 into which extends the hook end 55 of a pawl pivoted on a shaft 56 journaled between the walls 22 and 33. The shafts 34 and 35 carry pulleys 34' and 35' surrounded by cables 34^a and 34^b which are normally pulled downwardly by weights 34^c and 34^d. After the rotary movement of the disc has been stopped at 48 the weights return the discs in the opposite direction. This return movement is prevented when the hook ends 55 are engaged by teeth 57 carried by the discs.

The conductors 58 and 59 leading to the motor have switches 60 inserted in them beneath the rear ends of the shafts 34 and 35. These switches are normally opened whereby the motor is rendered inoperative. Each switch comprises a spring pressed contact

member 61 engageable by a cam 62 carried at the rear end of the corresponding shaft 34 or 35. When the shaft is returned by the crank 42 in the manner already described, the corresponding cam 62 presses the member 61 inwardly and closes the switch. The compartment 43 may be enclosed within a cover 65 pivoted to the front wall 22 as shown in Figures 1 and 2. In this case the conductor 66 connected to the side of the motor opposite the switches above referred to contains a similar switch 67 having an outwardly sprung pressed contact member 68 normally holding the switch open. This member is engageable by a curved finger 69 carried at the inner edge of the door and adapted to press the member 68 inwardly when the door is closed, thereby closing the circuit. Due to this construction, the pump cannot be operated unless the member 68 is pressed inwardly, which occurs when the door covering the discs is closed.

The motor is now set into operation and the piston 5 is raised through the action of pinion 32 and rack 21, whereby liquid is expelled from the tank. The rack carries trips 63 and 64 adapted to lift the pawls and release the hooked ends 55 from the teeth 57. It will be noted that the trip 63 is spaced at a shorter distance from the top of the rack than the member 64. When a key is inserted in the disc the pump will operate until the trip 63 rises to engagement with the corresponding pawl. Similarly, if a key is inserted in the disc 37, delivery of liquid will take place until the trip 64 releases its corresponding pawl. Due to the difference of position of the trips on the rack, it follows that different quantities of liquid will be delivered in accordance with the disc that is actuated. For example, the trips may be so disposed on the rack that operation of the discs 36 and 37 will permit delivery of one gallon and five gallons respectively. The keys for releasing the discs will obviously differ from one another in construction so that they cannot be used interchangeably for obtaining either quantity of liquid.

When the motor is stopped after elevating the piston, the weight of the latter acting on the fluid in the cylinder 2 causes the valves 7 to open. The piston thus descends by its own weight, since the flow of liquid therethrough is not obstructed.

To the housing 14 is attached a solenoid 70 lying at the inner side of the wall 33, as shown in Figures 2^a, 2^b and 20. The solenoid is connected in series with the motor circuit, as shown in Figure 19. The core of the solenoid projects through the bottom of the latter in the nature of a stem 71, to which is pivoted a latch 72 projecting through an aperture 73 in the wall 33 and pivoted to said wall. A keeper 74 is secured

to a side of the door 65 and projects through the opening 75 in the wall 22 whereby it is engageable by the latch 72. When the motor circuit is completed by the closing of the switch 67 upon closing of the door 65, the solenoid is energised and the stem 71 is pulled upwardly to bring the latch in engagement with the keeper. The door is thus locked and can not be opened until the circuit is broken at the switches 60 when the discs 36 and 37 have returned to their initial position. The cranks 42 are thus rendered inaccessible during the operation of the pump. If they could be reached while the pump is in motion, they could be turned backwards before the discs are locked, whereby the pump could be caused to effect an indefinite number of incomplete strokes by the insertion of a single key. In order that the device shall deliver only the specified amount of liquid for one coin, it is essential that the cranks be made inaccessible during the operation of the device.

While a specific embodiment of the invention has been illustrated and described, it is to be understood that various alterations in the details of construction may be made without departing from the spirit of the invention as indicated by the appended claims.

Having thus fully described the invention, what I claim as new and desire to protect by Letters Patent is:—

1. A liquid dispensing apparatus comprising a housing, a pump disposed within said housing, a motor for actuating said pump, a switch disposed in the motor circuit, a disc rotatably supported by the housing and adapted to be locked thereto, and an operative connection between the disc and the switch for closing the motor circuit.

2. A liquid dispensing apparatus comprising a housing, a pump disposed therein, a disc rotatably supported by the housing and adapted to be locked thereto, said disc being adapted to control the operation of the pump, said disc being adapted to receive a key for unlocking it from the housing, a receptacle disposed beneath the disc, a flap pivoted to the receptacle, and a cam carried by the disc and adapted to engage said flap for extracting the key from the disc.

3. A dispensing apparatus comprising a housing, a pump disposed therein, a disc rotatably supported by the housing and adapted to be locked thereto, said disc being adapted to control the operation of the pump means for returning the disc to normal position after rotation, means for holding said disc against return movement, and a trip member actuated from said pump for releasing said last named means.

4. A liquid dispensing apparatus comprising a housing, a pump disposed therein, said pump comprising a cylinder, a piston and a

piston rod, a rack extending from said rod, a motor disposed within the casing and operatively connected to said rack, a disc rotatably supported by the housing, a switch in the motor circuit, an operative connection between the disc and the switch, means for returning said disc after rotation, means for holding said disc against return movement, and a trip carried by said rack for releasing 10 said last named means.

5. A liquid dispensing apparatus containing a housing, a pump disposed therein, said pump comprising a cylinder, a piston and a piston rod, a rack extending from said rod, a motor disposed within the casing and operatively connected to said rack, a disc rotatably supported by the housing, a switch in the motor circuit, an operative connection between the disc and the switch, means for returning said disc after rotation, a tooth carried by said disc, a pawl pivoted to the housing and adapted to engage said tooth for holding the disc against return movement, and a trip carried by the rack and 20 adapted to release said pawl from the tooth.

6. A liquid dispensing apparatus comprising a housing, a pump disposed therein, a motor for actuating said pump, a switch in the motor circuit, a shaft rotatably supported in the casing, a disc carried by said shaft, a lock carried by the disc and adapted to secure the disc against rotation, and a cam carried by said shaft and adapted to close the switch upon rotation of the disc.

35. 7. A liquid dispensing apparatus comprising a housing, a pump disposed therein, a motor for actuating said pump, a switch in the motor circuit, a shaft rotatably supported in the casing, a disc carried by said shaft, a lock carried by the disc and adapted to secure the disc against rotation, a cam carried by said shaft and adapted to close the switch upon rotation of the disc, means for returning said disc to normal position, 40 means for holding said disc against return movement, and a trip operable by the pump mechanism for releasing said last named means.

8. A liquid dispensing apparatus comprising a housing, a pump disposed therein, said pump comprising a cylinder, a piston and a piston rod, a rack extending from said piston rod, a shaft journaled in the housing, a disc carried by said shaft and adapted to be locked with reference to the housing, means for returning said disc to normal position after rotation, means for holding the disc against return movement, a trip carried by the rack for releasing said last named means, 50 a motor for actuating said pump, a switch in the motor circuit, and means carried by the shaft for closing said switch upon rotation of the disc.

65. 9. A liquid dispensing apparatus comprising a housing, a pump disposed therein, said

pump including a cylinder, a piston, a piston rod and a pump driving mechanism, a rack extending from said rod, a pair of discs rotatably supported in the casing and means connected with said discs for controlling the 70 pump driving mechanism, means for returning said discs to normal position after rotation, means for holding said discs against return movement, and a pair of trips carried by the rack and adapted to release said 75 last named means, said trips being spaced at unequal distances from the upper end of the rack.

10. A liquid dispensing apparatus comprising a housing, a pump disposed therein, 80 said pump including a cylinder, a piston, a piston rod and a pump driving mechanism, a rack extending from said rod, a pair of discs rotatably supported in the casing and means connected with said discs for controlling the pump driving mechanism, means for returning said discs to normal position after rotation, a tooth carried by each disc, 85 a pair of pawls supported by the housing and adapted for engagement by said teeth 90 whereby the discs are held against return movement, and a pair of trip members carried by the rack and adapted to release said pawls, said trips being spaced at unequal 95 distances from the upper end of the rack.

11. A liquid dispensing apparatus comprising a housing, a pump disposed within said housing, a motor for actuating said pump, a switch disposed in the motor circuit, a disc rotatably supported by the housing and adapted to be locked thereto, an operative connection between the disc and the switch for closing the motor circuit, an electromagnet supported by the housing and connected into the motor circuit, a door pivoted to the housing and adapted to cover said disc, and a locking device carried by the door and electromagnet and adapted to open when said switch is opened.

12. A liquid dispensing apparatus comprising a housing, a pump disposed within said housing, a motor for actuating said pump, a switch disposed in the motor circuit, a disc rotatably supported by the housing and adapted to be locked thereto, an operative connection between the discs and the switch for closing the motor circuit, a door pivoted to the housing and adapted to cover said disc, a second switch provided in the motor circuit and adapted to close upon 115 closing of the door, an electromagnet supported by the housing and connected into the motor circuit, and a locking device carried by the door and electromagnet and adapted to open when said first named 120 switch is opened.

In witness whereof I have hereunto set my hand.

ALFRED JOSEPH SEALE.
